(57) **CLAIM**

We claim the ornamental design for a head mounted display, as shown and described.

DESCRIPTION

FIG. 1 is a front perspective view of the head mounted display comprising the present invention;
FIG. 2 is a front elevation view thereof;
FIG. 3 is a rear elevation view thereof;
FIG. 4 is a right side view thereof;
FIG. 5 is a left side view thereof;
FIG. 6 is a top view thereof;
FIG. 7 is a bottom view thereof;
FIG. 8 is a bottom perspective view thereof;
FIG. 9 is a bottom front perspective thereof worn on a user; and,
FIG. 10 is a bottom front perspective view thereof worn on a user with the goggles rotated to a raised position.
Broken lines shown in the drawings illustrate portions of the head mounted display, and form no part of the claimed design.
